UNITED STATES PATENT OFFICE.

GEORGE FREEMAN, OF NEW YORK, N. Y.

DIMMER WALL SWITCH.

Application filed April 1, 1927. Serial No. 180,199.

This invention relates to electric light switches and more particularly to a wall switch for controlling the lights of a room and having means therein whereby the intensity of the electric current supplied to individual lamps may be regulated at will.

One of the objects of the invention is to provide a switch of this character so arranged that the lights may be dimmed, 10 brightened or turned on or off gradually or abruptly.

Another object of the invention is to provide a device of this character having a resistance coil and a revolvable contact arm 15 whereby while one end of said arm is in contact with the resistance coil the opposite end is out of contact and vice versa.

Other objects will appear as the disclosure progresses. The drawings are intended 20 merely to indicate a possible embodiment of the invention. It is obvious that the actual needs of manufacture may necessitate certain mechanical changes. It is therefore not intended to limit the invention to the embodiment illustrated, but rather to define 25 such limits in the appended claims.

For a more detailed understanding of the invention, attention is now called to the drawings in which a preferred embodiment 30 is shown illustrated.

In general the device consists of a housing having therein a resistance coil, means to position the coil in the correct position, a contact arm arranged to contact with the 35 coil, and a knob on the exterior of the housing fixed on the same shaft with the contact arm for manually revolving said arm clockwise or counter-clockwise.

For a more detailed understanding of the 40 invention, attention is now called to the drawings in which a preferred embodiment is shown illustrated.

Figure 1 is a front view of the switch.

Fig. 2 is a similar view as Fig. 1 with a 45 portion of the switch plate broken away.

Fig. 3 is a detail of the core and resistance coil.

Fig. 4 is a section on line 4—4 of Fig. 1, and

50 Fig. 5 is a section on line 5—5 of Fig. 1. Referring to the drawing in detail in which like reference characters denote like parts throughout the specification, numeral

1 designates the outlet box, 2 the switch housing and 3 the core on which the resistance wire 4 is wound.

The core is made from a non-conducting material and provided with continuous evenly spaced grooves 5 into which is tightly wound the resistance wire. (See Fig. 60 3.) The ends of the wire are fastened under the tightening screws 6 at the top and bottom of the core. With the exception of the contact portion 7 of the core where the resistance wire is exposed, the entire winding 65 is treated with an insulating, heat-resisting, baked enamel finish. This enamel finish serves not only as an insulation of all sides except the contact surface 7, but aids in keeping the spacing of the coil rigid.

To support and fix the position of the core in the exact center of the housing 2 a pair of leveling screws 8 are provided. As noted in Fig. 4 the screws are threaded at the ends and fit in the top and bottom of 75 the core. By revolving the screws clockwise or counter-clockwise the vertical position of the core can be accurately adjusted.

Arranged to contact with the resistance coil 4 is a contact arm 9 fixed on the shaft 80 10. The shaft is adapted to revolve in a bushing 11 of a conducting metal housed in the switch plate 12 made of a non-conducting material. At the outside end of the shaft is fastened a control knob 13 made 85 from a phenol condensation compound for manually turning the contact arm 9. Placed upon the inner end of the bushing 11 is a contact element 14 attached to one of the cables 15, the other end of the cable being 90 connected to another cable 16 which leads to the source of current. For positioning the shaft 10 and its associated elements in place a lock nut 17 is provided. Numeral 18 designates a conducting element leading 95 from the bottom end of the resistance wire to the cable 19 leading to the lighting fixtures. At the top of the outlet box the cables 16 and 19 enter a standard flexible metallic conduit and are supported by a cable 100 clamp 20.

As noted in Fig. 5 the left hand side 21 of the front of core 3 is offset so that when one end of the arm is in contact with the resistance wire the other end is free to idle. 105 To ventilate the interior of the switch a pair

of slotted openings 22 are formed in the plate 12. Engraved on the knob 13 is a directional line 23 which corresponds with the position of the contact arm. Co-operating with this line are legends "Off", "Dim" and "Bright" engraved in the plate 12.

The operation of this device is as follows:

As indicated in Figs. 1 and 2 the knob 13 is shown in the "off" position. When the 10 knob is turned clockwise, the upper end of the arm 9 will contact with the resistance wire, close the electrical circuit and thereby turn on the lights very dim. As the knob continues to turn the lights become brighter 15 and brighter until the contact arm reaches a point near the bottom of the coil which corresponds to the brightest condition of the lights.

In the meantime the opposite end of the 20 contact arm has idled, passing in front of the offset portion of the core without making a contact. To turn off the lights abruptly, another slight turn of the knob in the same direction and the contact arm will be 25 off the coil and the circuit opened. This will bring the arm to the "off" position again.

To turn the lights off gradually, the knob 30 is turned in the opposite direction, counter-clockwise, from the full bright position to the point where the contact arm ceases to touch the coil. Either part of the double contact arm can be used for making contact, so that it is not necessary to turn the 35 knob through a complete revolution before starting the gradual brightening process all over again. Similarly, to turn the lights on full without going through the gradual brightening process, a slight turn in the 40 counter-clockwise direction is all that is necessary.

It will thus be seen that I have provided a simple and efficient dimmer switch to control the lights of a room so arranged that 45 a single knob is used to brighten or dim the lights or turn them on or off. The lights can be dimmed to suit the occasion, obviating the necessity of turning off individual lamps to reduce the glare. Also this device 50 does away with unsightly key sockets and pull chains, which mar the decorative effect of an otherwise beautiful lighting fixture, thus making the fixture less expensive.

Having thus described my invention I 55 desire to claim:

1. In a wall switch of the class described for controlling remote electric light bulbs including a resistance coil having an offset portion, a contact arm having two contact 60 points at the ends and pivoted adjacent the center of said coil, the ends of said contact arm being equidistant from the pivoting point, means for gradually lighting and dimming said lights, and means for abruptly lighting and dimming said lights.

2. In a wall switch of the class described for controlling remote electric light bulbs including a revolvable contact arm and a resistance coil having an offset portion, said contact arm having two contact points at 70 the ends and pivoted adjacent the center of the coil, the ends of said contact arm being equidistant from the pivoting point, the said lights adapted to be turned on or off by the revolution of said arm. 75

3. In a wall switch of the class described for controlling remote electric light bulbs including a revolvable contact arm and a resistance coil having an offset portion, said contact arm having two contact points at 80 the ends and pivoted adjacent the center of the coil, the ends of said contact arm being equidistant from the pivoting point, and means to gradually light and dim and abruptly light or extinguish said lights, by 85 the turning of said contact arm.

4. In a device of the class described, a single resistance coil, a pivoted contact arm having contact points at the opposite ends, and means to contact one end of the contact arm at a time with the said resistance coil, for making and breaking an electric circuit when the said arm is revolved. 90

5. In a device of the class described, a resistance coil wound on a core, a pivoted contact arm having contact points at the opposite ends and pivoted adjacent the center of said coil and adapted to contact with said resistance coil for making and breaking an electric circuit, the ends of said contact arm 100 being equidistant from the pivoting point, the said core having an offset portion, so only one end of said arm will contact with said resistance coil at one time. 95

6. In a device of the class described, a resistance coil wound on a core, a housing, for said core, adjusting screws for positioning said core, a pivoted contact arm adapted to contact with said resistance coil for making and breaking an electric circuit, the said 110 core having an offset portion so only one end of said arm will contact with said resistance coil at one time, the opposite end being free to idle. 105

7. In a device of the class described, a resistance coil wound on a core, a housing, for said core, the top and bottom of said core supported by adjusting screws, a pivoted contact arm adapted to contact with said resistance coil for making and breaking 115 an electric circuit, the said core having an offset portion, so only one end of said arm will contact with said resistance coil at one time, the opposite end being free to idle, a switch plate at the front of said housing 120 and a pair of slots within the said switch plate for ventilating the interior of said switch. 125

8. In a switch of the class described for controlling the circuit of remote lights, the 130

- combination with a resistance coil having an offset portion, of a pivoted contact arm having the contacts at the opposite ends and pivoted adjacent the center of the coil for 5 contacting with said coil for making and breaking said circuits, the ends of said contact arm being equidistant from the pivoting point, the said arm adapted to gradually increase the intensity of said lights when 10 turned clockwise and to suddenly turn on the lights when turned counter-clockwise.
9. In a switch of the class described for controlling the electric circuit of remote lights, the combination of a resistance coil 15 having an offset portion, of a pivoted contact arm for contacting with said coil for making and breaking said circuit, the ends of said contact arm being equidistant from the pivoting point, the said arm pivoted adjacent the center of said coil and adapted to gradually decrease the intensity of the lights when turned counter-clockwise and to increase the intensity of the lights when 20 turned clockwise.
10. In a switch of the class described for controlling the electric circuit of remote lights, the combination of a resistance coil having an offset portion, of a pivoted contact arm for contacting with said coil for 25 making and breaking said circuit, the ends of said contact arm being equidistant from the pivoting point, the said arm pivoted adjacent the center of said coil and adapted
- to gradually turn on said lights, increase the intensity of the lights and suddenly turn off the lights when the said arm is turned clockwise. 35
11. In a switch of the class described for controlling the electric circuit of remote lights, the combination of a resistance coil 40 having an offset portion, of a pivoted contact arm for contacting with said coil for making and breaking said circuit, the ends of said contact arm being equidistant from the pivoting point, the said arm pivoted adjacent the center of said coil and adapted to suddenly turn on the lights, gradually decrease the intensity of the lights and turn off the lights when turned counter-clockwise. 45
12. In a switch of the class described for controlling the electric light circuit of remote lights, the combination of a resistance coil having an offset portion, of a pivoted contact arm having the contacts at the opposite ends for contacting with said coil, the 50 ends of said contact arm being equidistant from the pivoting point, the said lights adapted to be turned off from a dim to a bright light and to be turned off when the said arm is turned clockwise, and said lights 55 adapted to be turned on abruptly, gradually dimmed and turned off when said arm is turned counter-clockwise. 60

In testimony whereof I affix my signature.

GEORGE FREEMAN.
